Maya Schmidt
ATTORNEY.

UNITED STATES PATENT OFFICE.

CARL JOSEPH LISH, OF LOUISVILLE, KENTUCKY.

PHOTOGRAPHIC-PRINTING FRAME.

1,353,922.

Specification of Letters Patent. Patented Sept. 28, 1920.

Application filed March 19, 1920. Serial No. 367,083.

To all whom it may concern:

Be it known that I, CARL JOSEPH LISH, a citizen of the United States, residing at 1131 S. 12th St., Louisville, in the county of Jefferson and State of Kentucky, have invented certain new and useful Improvements in Photographic-Printing Frames, of which the following is a specification.

This invention relates to photographic printing apparatus, and its object is to provide such apparatus with a means for punching the prints with a pair of holes to enable a batch of prints to be trimmed simultaneously by placing the same on a cutting table having upstanding pins on which the prints are mounted by means of the punched out holes.

The object stated is attained by means of a novel combination and arrangement of parts to be hereinafter described and claimed, and in order that the same may be better understood, reference is had to the accompanying drawing forming a part of this specification.

In the drawing, Figure 1 is a plan view of the invention, and Figs. 2 and 3 are cross-sections on the lines 2—2 and 3—3 of Fig. 1.

The preferred embodiment of the invention has been shown, but it will be understood that various changes and modifications may be made without a departure from the spirit and scope of the invention as claimed hereinafter.

Referring specifically to the drawing, 5 denotes the casing of a photographic printing apparatus. The top of this casing supports a lid 6, and is also fitted with a hinged platen 7 for pressing the negative and the print paper in close contact with a glass 8 through which the rays of the light source (not shown) pass to the negative to effect the printing operation. The lid 6 serves as a support for certain parts to be presently described, and it has a movable section 9 seating in an opening 10 made in the lid, and carrying the glass 8. The walls of the opening 10 and the edges of the section 9 are rabbeted to prevent said section from dropping down through the opening. On top of the section 9 is secured a sheet metal plate 11 having a rectangular opening through which the glass 8 is exposed. This plate serves as a mask to outline the picture.

The plate 11 extends to one end of the section 9 and projects a short distance therefrom, and is here provided with a hinged

plate 12 the function of which will be presently described. An ordinary spring hinge connection 13 between the plate 11 and the plate 12 is provided.

To the projecting end of the plate 11 carrying the hinged plate 12, on the under side of the former, is fastened, by screws or other suitable means 14, a cross bar 15, projecting at its ends from the plate. The opening in the lid 6 in which the section 9 seats is continued to accommodate the projecting ends of the cross bar 15, and said ends carry depending guide pins 16 working in apertures 17 in a pair of superposed cross bars 18 and 19 respectively, bolted or otherwise secured, to the under side of the lid 6. Springs 20 are coiled around the pins 16 between the cross bars 15 and 18. It will be evident from the foregoing that the section 9 is yieldably supported in the opening in the lid 6, and it is normally held slightly elevated in said opening by the springs 20. The cross bars 18 and 19 are bolted together or otherwise rigidly connected; or a single cross bar may be used.

The cross bars 18 and 19 carry upstanding punch pins 21 positioned to enter apertures 22 in the cross bar 15, and registering apertures 23 in the plate 11, when the section 9 is forced downwardly in the opening 10. The plate 12 has apertures 24 adapted to register with the apertures 22 and 23, and is also provided with apertures 25 to seat the heads of the screws 14, when the plate is swung down. Springs 26 are coiled around the pins 21 between the cross bars 15 and 18, these openings having the same function as the springs 20 hereinbefore described.

In use, the negative and the print paper are placed on the glass 8, and so positioned that they lie at one end above the apertures 23. The platen 7 is now swung down to press the negative and the print paper in close contact with the glass. The under side of the platen is fitted with a felt or other pad as usual. When the platen 7 is pressed down it forces the plate 12 down on top of one end of the negative and the print paper, and upon continuing the pressure, the section 9 is forced down in the opening 10, whereupon the pins 21 are exposed through the apertures 23, and the negative and the print paper are forced over the same to punch two holes therein. When the platen 7 is swung upwardly, the plate 12 also swings back, as it is spring-hinged, and the

negative and print may now be removed. The print is thus formed with two holes near one of its edges. A number of prints so punched may be placed on a cutting table having a pair of upstanding pins on which the prints are mounted by means of the punched out holes. The entire batch of prints may thus be trimmed simultaneously and uniformly.

10 I claim:

1. In a photographic printing apparatus, a support having an opening, a negative and print paper supporting member movably mounted in said opening, and having apertures over which the paper is adapted to be positioned, punch pins carried by the support in line with the apertures, a presser plate hinged to the aforesaid supporting member and having apertures adapted to 15
- 20 register with the first-mentioned apertures, and a platen engageable with the support and with the presser plate for moving the supporting member and the presser plate in a direction to force the punch pins through the apertures thereof.
- 25 2. In a photographic printing apparatus, a support having an opening, a negative and print paper supporting member movably mounted in said opening, and having apertures over which the paper is adapted to be positioned, punch pins carried by the support in line with the apertures, a presser plate hinged to the aforesaid supporting member and having apertures adapted to 30

register with the first-mentioned apertures, 35 a platen engageable with the support and with the presser plate for moving the supporting member and the presser plate in a direction to force the punch pins through the apertures thereof, and means for normally holding the supporting member in elevated position.

3. In a photographic printing apparatus, a supporting member and a negative and print paper supporting member movable 45 relative to each other, punch pins carried by one of said members, the other member having apertures in line with said pins over which the paper is adapted to be positioned, and means for effecting a relative movement 50 of the aforesaid members to force the punch pins through the apertures and the print paper.

4. In a photographic printing apparatus, a supporting member and a negative and print paper supporting member movable 55 relative to each other, punch pins carried by one of said members, the other member having apertures in line with said pins over which the paper is adapted to be positioned, 60 and a platen for holding the negative and the print paper in printing position, said platen being also operable to effect a relative movement of the aforesaid members to force the punch pins through the apertures and 65 the print paper.

In testimony whereof I affix my signature.
CARL JOSEPH LISH.
